(57) **CLAIM**

I claim the ornamental design for a potty, as shown and described.

DESCRIPTION

FIG. 1 is a perspective view showing my new design comprising a potty;

FIG. 2 is a front elevational view of the potty of FIG. 1;
FIG. 3 is a back elevational view of the potty of FIG. 1;
FIG. 4 is a right side elevational view of the potty of FIG. 1;
FIG. 5 is a left side elevational view of the potty of FIG. 1;
FIG. 6 is a top plan view of the potty of FIG. 1; and,
FIG. 7 is a bottom plan view of the potty of FIG. 1.
The broken lines shown in the drawings illustrate environmental structure and form no part of the claimed design.
